CLAIM

The ornamental design for a female irrigation tubing connector, as shown and described.

DESCRIPTION

FIG. 1 is a top perspective view of a female irrigation tubing connector showing my new design;

FIG. 2 is a side view thereof, the opposite side being a mirror image;

FIG. 3 is a side view thereof, the opposite side being a mirror image;

FIG. 4 is a top view thereof; and,

FIG. 5 is a bottom view thereof.

The portions of the design shown in broken lines are environmental structure and form no part of the claimed design.
